COMBINED THERMOMETER AND PENCIL HOLDER

Fred Lowenthal, New York, N. Y.

Application November 1, 1957, Serial No. 48,310

Term of patent 14 years

(Cl. D52—7)

FIG.1.

FIG.2.

FIG.3.

Fig. 1 is a front elevational view of a combined thermometer and pencil holder embodying my new design;

Fig. 2 is a side elevational view of the same, and

Fig. 3 is a top plan view of the same.

I claim:

The ornamental design for a combined thermometer and pencil holder, as shown.
